UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,295,880.

Specification of Letters Patent.

Patented Mar. 4, 1919.

Application filed May 3, 1918. Serial No. 232,300.

To all whom it may concern:

Be it known that we, JOHN ROGERS FLANNERY and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it applies to make and use the same.

This invention relates to improvements in staybolt structures for boilers, and more particularly to the closure for the bearing sleeve,—the object of our present invention being to provide simple and efficient means for removably securing the cap to the sleeve in a manner to permit its quick removal and replacement to facilitate the rapidity of the work of testing staybolts for boilers.

With this and other objects in view, the invention consists in certain novel features of construction and combinations of parts as hereinafter set forth and pointed out in the claims.

In the accompanying drawings; Figure 1 is a longitudinal sectional view of a stay-bolt structure on the line 1—1 of Fig. 3 showing an embodiment of our invention; Fig. 2 is a side elevation; Fig. 3 is a plan view, and Fig. 4 is a view of a modification.

1 represents a bearing sleeve adapted for connection with a boiler sheet and provided 35 interiorly with a curved face 2 which serves as a bearing for the head 3 of staybolt 4.

The sleeve 1 may be provided at its outer end with a peripheral flange 5 forming an annular shoulder 6 and within the confines 40 of said flange, a seat 7 is provided for a cap or closure 8. This cap 8 is made partly spherical for the accommodation of the bolt head and its internal dimensions and configuration are such as to provide a suitable clearance space 9 for the head of the stay-bolt. A portion of the cap is made with an exterior angular configuration for the accommodation of a wrench, and said cap is provided at or near its edge with a plurality 45 of lateral shoulders 10 (three such shoulders being shown in Fig. 3) adapted to overlie the flange 5 of the bearing sleeve.

A ring 11 is threaded on the bearing sleeve

1 and formed with a shoulder 12 to engage the shoulders 6 on said sleeve to limit the outward movement of said ring. The ring 55 11 is made with a plurality of jaws 13 (three such jaws being shown in Fig. 3) and the lips 14 of said jaws are adapted (when the parts are in locked position) to overlie the 60 shoulders 10 on the cap.

Instead of providing the cap with three lateral shoulders 10, it may be formed with two shoulders and the ring 11 made with two jaws as shown in Fig. 4.

The locking ring 11 will be screwed on the bearing sleeve before the latter has been applied to the boiler sheet. When the bearing sleeve has been secured to the boiler sheet the cap will be placed in position with 70 the shoulders 12 alternating with the jaws 13 as shown in Fig. 3. The operator will now give the cap a partial turn so as to move the shoulders 12 behind the lips of the jaws 13. He will then turn the ring 11 75 slightly and thus cause the lips of the jaws to clamp down on the shoulders 12 and securely press the cap against its seat on the bearing sleeve. It is evident that by turning the locking ring in the reverse direction, the 80 jaws will become released from the shoulders on the cap and when the parts become disposed as shown in Fig. 3, the cap can be lifted off or removed outward from the bearing sleeve and thus expose the head of 85 the staybolt.

With our improvements the cap or closure can be removed very quickly and replaced and locked with equal promptness, and thus access to the staybolt for testing purposes 90 will be greatly facilitated.

Having fully described our invention what we claim as new and desire to secure by Letters-Patent, is:—

1. In a staybolt structure, the combination with a bearing sleeve having a cap seat, of a cap having a plurality of lateral shoulders, and a ring threaded on said sleeve and having a plurality of jaws to engage over the lateral shoulders of the cap, whereby the 95 cap may be quickly unlocked and removed without removing said ring from the bearing sleeve.

2. In a staybolt structure, the combination with a bearing sleeve having an annular 100 flange at its outer end, of a cap to seat on

the bearing sleeve, said cap having a plurality of lateral shoulders to overlie the annular flange of the sleeve, and a ring threaded on the sleeve in rear of said annular flange and provided with a plurality of jaws having lips to overlie the lateral shoulders on the cap.

In testimony whereof, we have signed this

specification in the presence of two subscribing witnesses.

JOHN ROGERS FLANNERY.
ETHAN I. DODDS.
